UNITED STATES PATENT OFFICE.

WILLIAM EVERETT VER PLANCK AND LEO V. STOELTZLEN, OF ERIE, PENNSYLVANIA,
ASSIGNORS TO GENERAL ELECTRIC COMPANY, A CORPORATION OF NEW YORK.

INTERNAL-COMBUSTION ENGINE.

1,157,914.

Specification of Letters Patent.

Patented Oct. 26, 1915.

Application filed June 6, 1914. Serial No. 843,557.

To all whom it may concern:

Be it known that we, WILLIAM EVERETT VER PLANCK and LEO V. STOELTZLEN, citizens of the United States, residing at Erie, 5 in the county of Erie, State of Pennsylvania, have invented certain new and useful Improvements in Internal-Combustion Engines, of which the following is a specification.

10 There is at the present time a type of engine having at least one pair of cylinders, each provided with two pistons arranged to move toward and away from each other as they transmit power to the crank shaft. 15 The inner pistons, or those adjacent the shaft, are directly connected thereto by connecting rods. Each of the outer pistons is connected to an inner piston in the adjacent cylinder by a pair of diagonal rods, one in 20 the front and the other in the rear of the cylinder. Such an engine requires very exact workmanship in the making of the diagonal connecting rods and in the means for uniting them with the connecting rods that 25 unite the inner pistons with the main crank shaft. If there is the slightest difference in length of these diagonal rods or if the bearings of one of the rods wear more than another, it causes the relatively movable 30 parts to bind to a greater or less extent and thus cause undue wear. The same effect may be brought about to a lesser degree by unequal expansion of the diagonal rods.

Our invention has for its object to overcome the defect above mentioned and to provide a self-compensating or self-adjusting connection between the diagonal rods and the connecting rods that are connected to and drive the main shaft.

40 Our invention is applicable to engines utilizing steam or other elastic fluid as a source of power, and also to engines of the internal combustion type utilizing gas, gasolene, or other motor spirits, and also 45 the heavier oils. It may also be used in reciprocating apparatus for compressing air and other gases.

In the accompanying drawing which illustrates one of the embodiments of our invention, Figure 1 is a side view of a two-cycle internal combustion engine with certain of the parts broken away; Fig. 2 is a vertical section of the same taken in a plane per-

pendicular to the crank shaft; Fig. 3 is a detail sectional view showing the means for connecting the inner piston and one cylinder with the outer piston and the adjacent cylinder; and Fig. 4 is a perspective view of the gimbal which connects the diagonal rods to the inner piston.

5 indicates the casing of the engine, and supported thereby are cylinders 6 and '7. Only two cylinders are shown, but a greater number may be provided if desired and arranged vertically or horizontally. Each cylinder has an extension at the top and bottom to form suitable guides for the relatively long trunk pistons, and these extensions are slotted as at 8 and 9 to receive the outer wrist pin 10 and the inner wrist pin 11. 70 Located within each cylinder is a pair of oppositely moving trunk pistons, the outer one 12 being connected to the wrist pin 10, and the inner one 13 to the wrist pin 11. It will be noted that the wrist pins 10 and 11 occupy positions at right angles to each other. To the wrist pin 11 is attached a connecting rod 14 whose lower or inner end is connected to the crank 15 of the main shaft 16.

80 As will be seen best in Fig. 1, the outer piston in one cylinder is connected by a pair of diagonal rods 17 with the inner piston in the adjacent cylinder, thereby permitting the use of four pistons with only 85 two cranks. The upper ends of each pair of rods 17 and 18 are connected to the wrist pins 10 in any suitable manner. The lower ends are provided with a special connection. Surrounding the lower end of each of the 90 cylinders is an annular member 19 having trunnions 20 to receive the inner ends of a pair of diagonal rods. Formed in the ring and in the plane of the trunnions are two openings 21 to receive the inner wrist pin 11. 95 When the wrist pin is in position as shown in Figs. 1 and 3 it will be observed that its axis and that of the trunnions 20 are at right angles, and also that said pin forms a common means for connecting the connect-

100 ing rod with each inner piston and for connecting the diagonal rods with said connecting rod. The annular member 19 and its trunnions and wrist pin 11 form in effect a gimbal joint between each pair of the 105 diagonal connecting rods 17 and its coöp-

erating piston. The annular member 19 is separated from the outer surface of the cylinder by a relatively small annular clearance space 22, which space is great enough, 5 however, to permit said annular member to rock slightly about the wrist pin 11, or about the trunnions 20. This arrangement will prevent binding or undue wear on the parts due to the fact that one of the rods 17 10 is slightly longer than its mate, to inaccuracies in boring one of the pistons and mounting the wrist pin in place, and to unequal wear of the rod bearings. The arrangement also provides for unequal expansion 15 of the diagonal rods 17.

We prefer to locate the gimbal joint within the chamber 23 which may also serve as the scavenging air receiver. Fuel is introduced into the combustion space between the 20 pistons by the fuel injector 24. The exhaust products leave the cylinder by the ports 25, and fresh air for scavenging purposes enters the cylinders by the ports 26, said ports being controlled by the pistons.

25 27 indicates the dome which incloses the air compressor that supplies low pressure air for scavenging purposes and high pressure air for injecting fuel into the combustion space against the compression pressure. 30 By extending the cylinders top and bottom and using long trunk pistons, we avoid the use of separate cross-heads and guides therefor. By utilizing gimbals the wrist pins 11 perform a double function; that is, 35 connecting the connecting rod 14 to an inner piston and connecting said rod to a pair of diagonal rods such as 17. The features above enumerated have the effect of reducing the number of parts required and 40 in simplifying and reducing the initial cost of the engine.

In accordance with the provisions of the patent statutes, we have described the principle of operation of our invention, together 45 with the apparatus which we now consider to represent the best embodiment thereof; but we desire to have it understood that the apparatus shown is only illustrative and that the invention can be carried out by 50 other means.

What we claim as new and desire to secure by Letters Patent of the United States, is:—

1. In an engine of the character described, 55 the combination of a pair of cylinders, oppositely moving pistons in each cylinder, a crank shaft, a connecting rod between each of the inner pistons and the shaft, a pair of diagonal rods that connects each of the outer pistons with the inner piston in an adjacent cylinder, and a universal coupling interposed between each pair of diagonal rods and the inner piston movable therewith.

2. In an engine of the character described, 60 the combination of a pair of cylinders, oppositely moving pistons in each cylinder, a

crank shaft, a connecting rod between each of the inner pistons and the shaft, a pair of diagonal rods that connects each of the outer pistons with the inner piston in an adjacent cylinder, and a universal coupling 70 that is pivotally connected to each pair of diagonal rods and also pivotally connected to the inner piston and movable therewith.

3. In an engine of the character described, 75 the combination of a pair of cylinders which are slotted at their inner ends, oppositely moving pistons mounted in each cylinder, a crank shaft, a connecting rod between each inner piston and the shaft, a wrist pin for each connecting rod and its piston which 80 extends through the slots in the cylinder, a member which surrounds each cylinder and is connected to an inner piston by the extensions of said wrist pins, and a pair of diagonal rods for each outer piston that are 85 pivotally connected to one of said members.

4. In an engine of the character described, 90 the combination of a pair of cylinders which are slotted at their inner ends, oppositely moving trunk pistons mounted in each cylinder, a crank shaft, a connecting rod between each inner piston and the shaft, a wrist pin for each connecting rod and its piston which 95 extends through the slots in the cylinder, and a gimbal that is connected to each pair of diagonal rods and also to a wrist pin.

5. In an engine of the character described, 100 the combination of a pair of cylinders, oppositely moving pistons mounted in each cylinder, a crank shaft, a connecting rod between each inner piston and the shaft, annular members each of which is pivotally connected to one of the inner pistons, and a pair of diagonal rods for pivotally connecting each of the outer pistons to one of 105 said members, the axes of the connections between each member and its diagonal rods and piston being at right angles.

6. In an engine of the character described, 110 the combination of a pair of cylinders, each of which is slotted at opposite ends, oppositely moving trunk pistons mounted in each cylinder, a crank shaft, a connecting rod between each of the lower pistons and the shaft, a ring which surrounds the inner end 115 of each of the cylinders, a wrist pin which extends diametrically through each ring and slots in the cylinder and connects a piston and connecting rod, a wrist pin that extends through each of the outer pistons and the slots in the outer end of the cylinder, a pair of diagonally arranged rods that are connected to each of the last named pins, and trunnions on each ring that serve as 120 fulcra for the diagonal rods.

7. In an engine of the character described, 125 the combination of a pair of cylinders, oppositely moving pistons mounted in each cylinder, a main crank shaft, a pair of diagonally arranged rods for connecting each 130

outer piston with an inner piston in an adjacent cylinder, a connecting rod for connecting each of the inner pistons with a crank on the shaft, and a wrist pin which connects each of said inner pistons to its connecting rod and also connects a pair of diagonal rods thereto.

In witness whereof, we have hereunto set our hands this 3rd day of June, 1914.

WILLIAM EVERETT VER PLANCK.
LEO V. STOELTZLEN.
